CLAIM

The ornamental design for an implement for finishing joints between tiles, as shown and described.

DESCRIPTION

FIG. 1 is a side elevational view of an implement for finishing joints between tiles showing my new design; FIG. 2 is an end taken from the left side of FIG. 1; FIG. 3 is an end view taken from the right side of FIG. 1; and

FIG. 4 is a perspective view thereof illustrating the left end of the implement separated therefrom.
A cross-sectional view taken at any point between the right and left ends of FIG. 1 would be circular.
